UNITED STATES PATENT OFFICE

ALVA MAHANNAH, OF SEDGWICK, KANSAS

END GATE

Application filed July 7, 1930. Serial No. 465,883.

My invention relates to improvements in endgates for vehicle beds or the like.

An object of my invention is to provide an endgate having a removable portion.

5 A further object of my invention is to provide an endgate having a removable portion and means to rock the same to and from engagement.

10 A still further object of my invention is to provide an endgate that the method of operation may be exercised by means securely attached but operatively arranged avoid loss or displacement of any of the parts thereof.

15 15 A still further object of my invention is to provide an endgate that will divide approximately in the center horizontally and means to rock the lower portion thereof so that the opening closed thereby will be unobstructed.

20 A still further object of my invention is to provide an endgate comprising two parts to enclose the area between the sides and bottom of the vehicle bed and may be placed and removed as a single unit and having means to secure the same rigidly in position and grain tight.

25 30 A still further object of my invention is to provide an endgate having a portion removably arranged and means to lock the same in a closed position.

35 A still further object of my invention is to provide an endgate having a portion removable by means that may be applied as a grain door for box cars in transportation of grain and operatively arranged as herein set forth, but proportioned to engage with the door posts and floor of the car.

40 These and other objects will be hereinafter more fully explained, reference being had to the accompanying drawings which form a part of this specification, and in which like characters apply to like parts in the different views.

45 Referring to the drawings.

Fig. 1 is a side elevation of a fragmentary portion of a motor driven truck of the dump type, and partly in section.

50 Fig. 2 is a rear end view of Fig. 1.

Fig. 3 is an inside view of the endgate, the

bottom and sides being in cross and taken on line 3—3 in Fig. 1.

Fig. 4 is an enlarged sectional view taken on line 4—4 in Fig. 2 with the lower portion of the endgate being partially rocked from engagement. 55

Fig. 5 is a similar view showing the movement and open position of the endgate.

Fig. 6 is an enlarged sectional view taken on line 6—6 in Fig. 2 with the hinges and outer portions of the bail being removed. 60

My invention herein disclosed consists of an endgate 1 having an auxiliary portion 2 that is removably arranged and pendently supported at each end thereof by a bail like 65 structure 3 having oppositely disposed portions axially aligned and trunnioned in the eye of a hinge member 4 respectively. The said hinges being securely attached in close proximity to each end of the auxiliary endgate. The said bail outwardly extending at right angles from each of the axially aligned portions is a segmental right angled bend axially aligned with respect to each other, the last said right angled portions pivotally 70

engaging in the outwardly extending leg of an L shaped member 5 transversely positioned and in close proximity to each end of the endgate and extending thereacross and functioning further as a supporting means for 75

each of the downwardly extending legs A of the endgate; it being understood that by 80

rocking the bail as shown by dotted lines B that the auxiliary endgate is moved to and from engagement as shown in Figs. 1, 4, and 5. It is further understood that the said auxiliary endgate is pendently supported when rocked from engagement as shown by dotted lines C, and when rocked to its extreme upward position in parallelism with 85

the endgate as shown in Fig. 5. The said auxiliary endgate is secured thereto by means of a dog 6 resiliently arranged and securely affixed to the upper edge and centrally positioned longitudinally. 90

When replacing the auxiliary member, the bail is rocked downward as shown in Fig. 4 and simultaneously therewith, the lower edge of the said auxiliary endgate is moved 95 inward and supported by a tongue 7 oblique- 100

ly extending outward and being integrally connected with one of the leg members 5 respectively, by which means the lower edge of the said auxiliary endgate is seated in alignment with the leg members A and to secure tight engagement of the upper edge thereof, the same is slightly beveled as at D to co-incide with a similar bevel of the endgate proper as at E, by which means the upper joint is made grain tight and the lower joint is brought to a snug engagement by the bail in its extreme downward position and being securely locked thru the medium of a pin 8 slidably engaging in a bracket 9, both ends of which are positioned outward at a right angle and in parallelism with each other. Each of said end portions being apertured to receive the pin slidably engaging therein, and the said pin is tensioned downward by a coil spring 10 wound thereon, the lower end seating on a cotter key 11 or the like, while the upper end seats on the upper leg of the bracket.

It is now clearly shown the method by which the bail is locked to avoid opening of the auxiliary portion of the endgate, and being so attached the auxiliary member is tensioned inward to snug engagement with a flange member 12 securely attached to each of the said leg members A and extending over the joint for the end portion of the auxiliary member to seat firmly thereon respectively, by which means the vertical end joints are made grain tight and being thus secured in closed position; the endgate proper may be removed and replaced as a single unit as it slidably engages between cleats 13 secured to the sides 14 of the bed and rigidly secured therein by a rod 15 passing thru apertures in the sides and in each of the L shaped members. The rod being shouldered at an end and threadly engaging at the other end by which means the sides of the bed are drawn toward each other for snug engagement with the endgate.

While I have described my invention as applied as an endgate for the bed of a truck I do not wish to be restricted to this alone as the same may be applied as a grain door for a box car and removably arranged in a similar way previously described, and the auxiliary endgate arranged to function in like manner and such other modifications may be employed as lie within the scope of the appended claim. Having fully described my invention what I claim as new and desire to secure by Letters Patent is:—

In an endgate for vehicle beds or the like, an endgate comprising an upper portion and a lower intermediate portion equally divided horizontally, the upper portion having a flanged leg aligned with each end thereof and an L shaped member oppositely positioned to the flange and extending longitudinally with the leg portion and across

the upper portion and near each end thereof, the L shaped member having a portion of one leg removed to near the lower end thereof, the remaining portion being turned outward functioning as a guiding means for the lower edge of the intermediate portion to alignment with the leg portions, and each of the L shaped members having an aperture aligned and centrally positioned with respect to the upper portion of the endgate, and a bail pivotally engaging therewith and means to pivotally engage an intermediate portion of each side of the bail with the top edge of the intermediate portion of the endgate, by which means the intermediate portion is raised to alignment with the upper portion with respect to the upper and lower edges of each, and a latch to bind the upper edges together to retain the same against retraction, a locking means attached near the lower edge of the intermediate portion, the locking means comprising a U shaped member having an aperture near the outer end of each of the leg portions to receive a pin slidably engaging therein, the pin having a spring wound thereon as a downward tensioning means therefor to retain the lower loop of the bail when positioned beneath the U shaped member, the bail functioning as a support extending across the intermediate portion when locked in a closed position.

In testimony whereof I affix my signature.

ALVA MAHANNAH.
